UNITED STATES PATENT OFFICE.

FRANCIS WINANS GIBSON, OF WEST ROXBURY, MASSACHUSETTS, ASSIGNOR TO H. D. BEACH COMPANY, OF COSHOCOTON, OHIO, A CORPORATION OF OHIO.

DISPLAY STAND.

Application filed May 12, 1924. Serial No. 712,608.

To all whom it may concern:

Be it known that I, FRANCIS W. GIBSON, a citizen of the United States, residing at West Roxbury, county of Suffolk, Commonwealth of Massachusetts, have invented certain new and useful Improvements in Display Stands, of which the following is a specification.

This invention relates to display stands, and particularly to a collapsible display stand. In such stands, it is desirable that the maximum amount of goods consistent with accepted merchandizing practices shall not only be supported for convenient display and access, but that the stand itself shall afford a maximum display surface for the display of advertising matter descriptive of the goods. Usually floor space is limited and hence any display stand must combine these requisites in a construction which will utilize only the minimum floor area. Experience has shown that the vertical type of display rack with superposed series of horizontal shelves is the type rack which most satisfactorily answers these requirements, and it is to this type of display rack that my present invention specifically relates. The ordinary display rack of this type, however, is usually a solid, rigidly connected structure and consequently not only lacks that capacity for expansion or contraction in respect to the shelf units, but requires considerable shipping and storage space because of its fixed bulk.

To the end, therefore, of providing a display rack of this general type, but which may be collapsed and nested and shipped as a flat, compact package, and conveniently assembled by the user in as many shelf units as occasion requires, I have devised my present invention.

According to it, the end uprights for the superposed shelf series consists of a pair of spaced substantially U-shaped members which provide spaced vertical front and rear guides and supports for the shelf units, which may be furnished in any desired number within the height limits of the uprights and horizontal floor engaging portions connecting said shelf guide supports. The individual shelves of the shelf series are formed to slidably fit over the upper ends of said guide supports, so as to be capable of ready assembly and disassembly, provision being made for limiting the sliding travel of the

shelves on said supports to insure proper spacement of the shelves relative to each other when the display stand is assembled. The shelves themselves are constructed to provide longitudinal panels for the display of advertising matter descriptive of the goods on sale, and these panels extend continuously across the front of the display stand so as to be readily legible by the prospective purchaser.

The construction and method of assembling and collapsing my display stand, together with a selected embodiment thereof which well illustrates the principles involved, is described and shown in the accompanying specification and drawings, and the characteristic features of novelty are particularly pointed out in the appended claims. Throughout the specification and drawings like reference characters are employed to indicate corresponding parts, and in the drawings:

Fig. 1 is a perspective view of a display stand in accordance with my invention and showing the stand set up for use.

Fig. 2 is a similar view showing the stand collapsed for shipment,

Fig. 3 is a development of one of the shelf blanks before it is bent to shelf form and

Fig. 4 is a section on the line 4—4 of Fig. 2.

I have indicated at 1 a pair of duplicate supporting members constituting the end uprights of the display stand. These uprights may be conveniently formed each of a round wire which is bent upon itself into substantially U-form to provide spaced front and rear vertically disposed shelf guide and supporting legs 2 and an intermediate horizontally disposed floor connecting foot 3 connecting said legs 2.

Slidable vertically on the guide supports 2 is a spaced superposed series of substantially hood-shaped shelves 4. Each shelf consists of a blank which is bent upon itself along the longitudinal fold lines 5 and 8 to provide a vertical back panel 6, a downwardly inclined bottom panel 7, and an upturned front panel 9 which is disposed at substantially right angles to the bottom panel 7 and against which the end walls of the boxes B on display are adapted to abut. The front panel 9 is again bent on the indicated fold line 10 to provide a substantially vertically disposed flange 11 which

constitutes a display surface adapted to bear advertising matter descriptive of the goods. The end edges of the panels 7 and 9 are notched as indicated at 12 and rolled upon themselves as indicated at 13 to eliminate sharp cutting edges. The end edges of the panels 6 and 11 are rolled upon themselves to provide tubular guides or bearings 14 adapted to slidably embrace the guide 10 supports 2 of the end uprights 1, the upper ends of said bearings 14 being preferably partially closed to limit the downward movement of the shelves on the uprights and thus insure proper spacement of the shelves in 15 the series relative to each other.

The uprights 1 rigidly spaced by the bent connecting portion 3, when so connected by the webs or flanges 6 and 11 of the superimposed shelves, constitute a double braced 20 frame for the shelves proper. The foot or base portions 3 in addition to their bearing and lower shelf stopping function, are rigid front-to-rear braces in the frame, while the flanges 6 and 11 of the shelves themselves 25 combine to complete a quadrilateral frame front and rear, this giving great strength to the structure when set up.

In collapsing the display stand, the individual shelves are slid upwardly along the 30 guide supports 2, and when disconnected therefrom, are nested one upon the other as shown in Fig. 2.

Obviously, as many shelf units as are desired may be assembled upon the guide 35 supports 2 and the spacement of these units may be varied, as desired. These and various other modifications in the form and arrangement of my stand may all be made within the spirit and scope of my invention 40 as defined by the appended claims.

What I therefore claim and desire to secure by Letters Patent is:

1. In a collapsible display stand, a pair 45 of detachable spaced U-shaped end uprights, of substantially the same size each comprising spaced substantially vertical front and rear shelf guide and supporting portions, and an intermediate substantially horizontal connecting floor-engaging portion, and a 50 series of spaced superposed shelves slidably mounted on said end uprights, each shelf being bent upon itself at its end edges to provide tubular guides and also being downturned adjacent its front and rear edges 55 whereby said guides may engage said uprights and means for limiting the downward sliding travel of the shelves on said end uprights whereby to insure proper relative spacement of the shelves in the series.

2. In a collapsible display stand, a pair of spaced end uprights, and a series of spaced 60 superposed shelves slidably mounted on said end uprights, each shelf comprising a blank bent upon itself to provide a substantially

hod-shaped article supporting portion and 65 a pair of substantially vertically disposed panels at the front and rear edges of said article supporting portion, said panels being bent upon themselves at their end edges to provide tubular guides adapted to slidably 70 embrace the end uprights and said guides being provided with means to limit the downward sliding travel of the shelves on said uprights whereby to insure proper relative spacement of the shelves in the 75 series.

3. In a collapsible display stand, a pair 80 of spaced U-shaped end uprights, each comprising spaced substantially vertical front and rear shelf guide and supporting portions and an intermediate substantially horizontal connecting floor-engaging portion, and a series of spaced superposed shelves 85 slidably mounted on said end uprights, each shelf comprising a blank longitudinally bent upon itself to provide a substantially hod-shaped article supporting portion and a pair of substantially vertically disposed panels at the front and rear edges of said article supporting portion, said panels being bent upon themselves at their end edges to provide tubular guides adapted to slidably 90 embrace the vertical guide portions of the end uprights, and said guides being provided with means to limit the downward sliding travel of the shelves on said end uprights whereby to insure proper relative spacement of the shelves in the series.

4. In a collapsible display stand, a pair 100 of spaced end uprights, and a removable series of spaced superposed shelves slidably mounted on said uprights, each shelf being bent upon itself at its end edges to provide tubular guides, and also downturned adjacent its front and rear edges, whereby said guides may engage and rigidly connect said uprights, said shelves when disengaged from said uprights nesting flatly one within the other.

5. In a collapsible display stand, a pair 110 of spaced end uprights, each comprising spaced substantially vertical front and rear shelf-guiding and supporting portions and an intermediate substantially horizontal 115 floor-engaging portion connecting said front and rear shelf-guiding portions, and a removable series of spaced superposed shelves slidably mounted on said uprights, each shelf being bent upon itself at its end edges 120 to provide tubular guides and also being downturned adjacent its front and rear edges whereby said guides may engage and rigidly connect said uprights, said shelves when disengaged from said uprights nesting flatly one within the other.

In testimony whereof I affix my signature.

FRANCIS WINANS GIBSON.
